UNITED STATES PATENT OFFICE.

MINER N. LOEHR, OF WARSAW, INDIANA.

THILL-COUPING.

SPECIFICATION forming part of Letters Patent No. 391,754, dated October 23, 1888.

Application filed May 24, 1888. Serial No. 274,905. (No model.)

To all whom it may concern:

Be it known that I, MINER N. LOEHR, of Warsaw, in the county of Kosciusko and State of Indiana, have invented a new and Improved 5 Thill-Coupling, of which the following is a full, clear, and exact description.

This invention relates to an improvement in thill-couplings, and has for its object to provide a thill-coupling which will be durable 10 and will not rattle.

The invention consists of a thill-coupling constructed and arranged as hereinafter described and claimed.

Reference is to be had to the accompanying 15 drawings, forming a part of this specification, in which similar figures of reference indicate corresponding parts in all the views.

Figure 1 is a plan view partly in section and broken away, showing a thill-coupling 20 constructed in accordance with this invention. Fig. 2 is a vertical section thereof on the line *x x*, and Figs. 3, 4, and 5 represent details thereof detached.

In the construction of this invention the 25 thill-iron 1 is connected to the axle-clip 2 by means of a screw-threaded bushing, 3, screwed into the threaded socket end 4 of the thill-iron 1, and having its ends projecting from the socket end 4 and bearing against the ears 5 of 30 the clip 2. The bushing 3 is formed with a square hole, 6, and the ears 5, with square holes 7, through which projects a correspondingly-shaped bolt, 8, having a screw-threaded end, 9, and retaining-nut 10. It will thus be 35 seen that the bushing 3 is held from turning by the square-shaped bolt 8, and that the socket end 4 of thill-iron 1 turns on the bushing 3. By tightening the nut 10 the ears 5 are

drawn against the ends of the bushing 3, thereby preventing rattling. As the ends of the bushing 3 are worn, the ears 5 may be drawn up 40 against them, as just described. The wear upon the screw-threaded parts of the bushing and socket 4 will be small, so that a durable coupling will be had and rattling thereof will 45 be avoided.

While I have described a specific construction of parts, I do not intend to limit myself thereto, as they may be varied without departing from the essential features of the invention. 50

Having thus fully described my invention, I claim as new and desire to secure by Letters Patent—

1. In a thill-coupling, the combination, with 55 a clip, of a thill-iron having a screw-threaded socket end, a screw-threaded bushing in the socket of the thill-iron, and a bolt passing through the ears of the clip and the bushing and locking the bushing from turning, sub- 60 stantially as described.

2. A thill-coupling consisting of thill-iron 1, having screw-threaded socket end 4, in combination with bushing 3, screwed into the socket end 4 and having ends projecting there- 65 from, and square hole 6, with axle-clip 2, hav- 70 ing ears 5, with square holes 7, and square- shaped bolt 8, projecting through holes 6 and 7 and secured by nut 10, the bushing 3 being located between the ears 5 of clip 2, substan- 75 tially as described.

MINER N. LOEHR.
